[57] CLAIM

The ornamental design for a garden arbor, as shown and described.

DESCRIPTION

FIG. 1 is a perspective view of a garden arbor showing my new design;

FIG. 2 is a front view thereof;

FIG. 3 is a side view thereof;

FIG. 4 is a top view thereof;

FIG. 5 is a rear view thereof.

The garden arbor is a seat with a surrounding structure upon which flowers may grow and climb.

FIG. 1

FIG. 2
